Primary Examiner—James Gandy**Assistant Examiner—Cathron B. Matta****[57]****CLAIM**

The ornamental design for the portable language translating machine, as shown and described.

DESCRIPTION

FIG. 1 is a perspective view of the portable language translating machine showing my new design in the open position;

FIG. 2 is a front elevational view thereof shown in the closed position;

FIG. 3 is a rear elevational view of FIG. 2;

FIG. 4 is a left side elevational view of FIG. 2;

FIG. 5 is a right side elevational view of FIG. 2;

FIG. 6 is a top plan view of FIG. 2; and,

FIG. 7 is a bottom plan view of FIG. 2.

The broken line showing of words is for illustrative purposes only and forms no part of the claimed design.
